UNITED STATES PATENT OFFICE.

WILLIAM C. FISHER, OF MIDDLETOWN, CONNECTICUT, ASSIGNOR TO THE RUSSELL MANUFACTURING COMPANY, OF MIDDLETOWN, CONNECTICUT.

BRAKE-SHOE.

1,078,040.

Specification of Letters Patent.

Patented Nov. 11, 1913.

Application filed August 14, 1912. Serial No. 715,055.

To all whom it may concern:

Be it known that I, WILLIAM C. FISHER, a citizen of the United States, residing at Middletown, in the county of Middlesex and

5 State of Connecticut, have invented certain new and useful Improvements in Brake-Shoes; and I do hereby declare the following to be a full, clear, and exact description of the invention, such as will enable others 10 skilled in the art to which it appertains to make and use the same.

This invention relates to improvements in brakes and more particularly to shoes therefor, one object of the invention being to so 15 construct a brake shoe as to enhance the longevity of the same and prevent the generation of heat.

A further object is to construct a brake shoe in such manner that the noise and wear 20 incident to the use of shoes made partly or wholly of metal, shall be reduced to a minimum.

25 A further object is to so construct a brake shoe as to enhance the durability of the same; afford adequate frictional contact with the wheel with a minimum amount of wear in a given length of time, and be capable of quick and ready application and renewal.

30 With these objects in view the invention consists in certain novel features of construction and combination of parts as hereinafter set forth and pointed out in the claims.

35 In the accompanying drawings; Figure 1 is a view showing the application of my improvements; Fig. 2 is a separate view of the shoe, showing its appearance before its application to the shoe head; and Fig. 3 is a 40 sectional view of the shoe.

1 represents a brake shoe head which may be of any preferred or conventional form, and to which my improved wearing shoe 2 is applied, as will be more fully hereinafter 45 explained.

The shoe 2 is made of asbestos fabric (preferably containing wire in its strands) comprising a plurality of superimposed plies securely united into a solid mass except 50 at the side portions, and treated with hardening material, such as a composition of heated sulfur and molasses, which will render the shoe very hard and durable but sufficiently pliant to permit it to be bent under

pressure, (with the use of a suitable former), to make it conform to the contour of the shoe head.

In constructing the shoe, I employ a plurality of superimposed plies 3 of woven fabric consisting of strands of asbestos containing wire. These superimposed plies are secured together (preferably by suitable binder threads) so as to form an integral body of suitable width to form the shoe. The side edges of the several plies are left free, as shown at 4, and the loose side portions of the several plies have progressively increasing width from the forward toward the rear face of the shoe.

The fabric shoe, constructed as above described, is rendered very durable by treatment with the hardening material as hereinbefore explained.

The body of the shoe may be bent by suitable means, to conform to the contour of the face of the head 1, and the free, laterally projecting side portions 4 of the plies will be bent, one upon another, over the sides of the head 1 and secured to the back of the latter by means of bolts 5 which pass through alining holes in the several lateral portions 4 and enter the body of the head 1. By making the free side portions of the plies of different widths, the free edges of these portions will aline, when secured, as will be readily understood.

With a brake shoe constructed and applied as hereinbefore described, a wearing face is afforded which will be yielding and avoid the noise and rattling incident to the use of shoes having metal engaging surfaces.

While the body of the shoe consists of woven fabric, still experience has shown that the same is very durable and at the same time, adequate frictional engagement with the wheel will be afforded to render the shoe very efficient in the performance of its functions.

Having fully described my invention what I claim as new and desire to secure by Letters Patent, is:—

1. A brake shoe comprising a plurality of superimposed plies of woven fabric secured together, each of said plies having free portions at the side edges.

2. A brake shoe comprising a plurality of superimposed plies of woven fabric secured

together and containing hardening material, the side portions of the several plies being free.

3. A brake shoe comprising superimposed 5 plies of woven fabric secured together and containing hardening material, the side portions of said plies being free, said free portions of the plies varying progressively in width.
- 10 4. The combination with a brake head, of a shoe comprising superimposed woven plies of asbestos secured together and containing

hardening material, the side portions of said plies being free and extending over the side edges of the head, and fastening means 15 for securing the shoe to the head.

In testimony whereof, I have signed this specification in the presence of two subscribing witnesses.

WILLIAM C. FISHER.
